JEWELRY BOX

John H. Ax, ½ London Leather Novelties, Inc.,
19 W. 18th St., New York, N.Y. 10011

Filed Mar. 22, 1965, Ser. No. 84,375

Term of patent 14 years

(Cl. D58—12.7)

FIG. 1 is a front perspective view of a jewelry box, showing my new design;

FIG. 2 is a front elevational view;

FIG. 3 is a rear elevational view;

FIG. 4 is an end elevational view;

FIG. 5 is a perspective view with the drawer rotated into a half open position; and

FIG. 6 is a perspective view thereof with the drawer rotated into a fully open position.

The dominant features of my design reside in the portion shown in full lines.

I claim:

The ornamental design for a jewelry box, as shown and described.
